ATTORNEY.

UNITED STATES PATENT OFFICE

GEORGE H. HOWARD, OF ALHAMBRA, CALIFORNIA

MOTOR STARTER DRIVE

Application filed November 30, 1931. Serial No. 578,090.

This invention relates to the driving means between the starting motor and an internal combustion engine. These means usually consist of a pinion which engages and disengages 5 a gear on the fly-wheel of the engine.

An object of my invention is to provide a starter drive which will positively engage and disengage the starting pinion when the electric starting motor is rotated.

10 Another object is to provide a starter drive of the character stated which is yieldably mounted and will not impart a shock to the electric motor or the teeth of the gear on the engine.

15 A further object is to provide a starter drive the spring of which also acts to move the pinion gear into and out of engagement when the motor is rotated.

20 A further object is to provide a starter drive including a spring which spring is readily removable and replaceable when broken.

25 Other objects, advantages, and features of invention may appear from the accompanying drawing, the subjoined detailed description, and the appended claims.

In the drawing:

Figure 1 is a fragmentary side elevation of the starter drive, electric motor, and fly-wheel.

Figure 2 is a longitudinal sectional view of the starter unit in released position.

Figure 3 is a sectional view taken on line 3, 3 of Figure 2.

35 Figure 4 is a view similar to Figure 2 but with the pinion in engaged position.

Figure 5 is a sectional view taken on line 5, 5 of Figure 4.

Figure 6 is a plan view of the starter unit 40 with parts broken away to show interior construction.

Referring more particularly to the drawing, the numeral 1 indicates the fly-wheel of an engine upon which the usual ring gear 45 2 is mounted. An electric starting motor

3 is mounted adjacent the fly-wheel 1 and is provided with the usual armature shaft 4. A sleeve 5 fits closely over the outer end of the armature shaft and is secured to said shaft by a screw or bolt 6. A housing 7 is 50 slidably mounted on the sleeve 5 and a pinion gear 8 is cut on the inner end thereof, which gear is adapted to mesh with the ring gear 2 to rotate the fly-wheel in starting the engine, all of which is usual and well-known 55 in the art.

The housing 7 is enlarged at its outer end, as at 9, to accommodate a pair of spirally formed springs 10. These springs are secured to the housing 7 at the forward end 60 thereof by fitting said springs into recesses 11 in said housing. The springs 10 are preferably of the flat type, that is, they are substantially rectangular in cross-section and the springs are so spaced apart that they form a 65 spiral track-way or thread in which pins 12, 12 are adapted to travel. These pins rise from the sleeve 5 and are either integral therewith or are secured thereto.

At the rear end the springs 10 are each bent 70 to form a stop 13 and the stops are then welded, or otherwise secured, to a plate 14, which plate slips over the sleeve 5. A pair of oppositely positioned lugs 15 are provided on the plate 14 and these lugs extend into enlarged 75 recesses 16 in the end of the housing 7. That is, the recesses 16 are so formed that the plate can rotate a short distance about the housing 5 against the tension of the springs 10, all of which will be further described.

80 A cover 17 fits over the outer end of the housing 7 and fits over the sleeve 5, thus holding the plate 14 and springs 10 against outward movement. The cover 17 can be either screwed onto the housing or it may be otherwise suitably secured.

85 In operation the housing 7 is in the position shown in Figures 1 and 2 with the pinion 8 disengaged from the gear 2. Now, as the motor 3 rotates, the pins 12 will travel in the 90

spiral path formed by the springs 10 and will therefore move the housing 7 forwardly and carry the pinion 8 into engagement, with the gear 2.

- 5 When the pins 12 engage the stops 13 the shock of this stop will be relieved because of the tension of the springs 10 and the motor will continue to rotate to drive the engine in starting the same without any shock. Also, 10 if the pinion 8 does not exactly engage the teeth of the gear 2 the spring 10 will yield a small amount so as to permit the motor to continue to rotate until the pinion has found a point where it can engage. It will be 15 readily seen that by removing the cover 17 the springs 10 can be easily removed and replaced when necessary.

Having described my invention, I claim:

1. In combination with an engine fly-wheel, a gear on the fly-wheel, a starting motor, an armature shaft on the motor of a starter drive comprising a housing slidably mounted on the armature shaft, a pinion on the housing, a pair of spirally wound springs in said housing, means removably securing said springs to the housing at one end thereof, pins rising from the shaft, said pins being adapted to extend between the springs, which springs form a spiral track-way, and a plate secured to the other end of said springs.
2. In combination with an engine fly-wheel, a gear on the fly-wheel, a starting motor, and an armature shaft on the motor of a starter drive comprising a housing slidably mounted on the armature shaft, a pinion on the housing, a pair of spirally wound springs in said housing, means removably securing said springs to the housing at one end thereof, pins rising from the shaft, said pins being adapted to extend between the springs, which springs form a spiral track-way, and a plate secured to the other end of said springs, lugs on the plate, said housing having recesses therein to receive the lugs, said recesses being larger than the lugs so that a rotary movement of the plate is permitted.
3. In combination with an engine fly-wheel, a gear on the fly-wheel, a starting motor, and an armature shaft on the motor of a starter drive comprising a housing slidably mounted on the armature shaft, a pinion on the housing, a pair of spirally wound springs in said housing, means removably securing said springs to the housing at one end thereof, pins rising from the shaft, said pins being adapted to extend between the springs, which springs form a spiral track-way, and a plate secured to the other end of said springs, lugs on the plate, said housing having recesses therein to receive the lugs, said recesses being larger than the lugs so that a rotary movement of the plate is permitted, and a cover extending over the shaft and against the plate and secured to the housing

whereby the plate and springs are held in position.

4. In combination with an engine fly-wheel, a gear on the fly-wheel, a starting motor, and an armature shaft on the motor, of a starter drive comprising a sleeve secured to the armature shaft, a housing slidably mounted on said sleeve, a pinion on the housing adapted to mesh with the gear on the fly-wheel, a pair of spirally wound springs in said housing, said housing having recesses therein to receive the inner ends of the spring, said springs being spirally wound to provide track-ways, a plate secured to the outer ends of said springs, and pins rising from said sleeve adapted to extend between the springs and guided thereby, whereby the housing is moved inwardly and outwardly.

5. In combination with an engine fly-wheel, a gear on the fly-wheel, a starting motor, and an armature shaft on the motor, of a starter drive comprising a sleeve secured to the armature shaft, a housing slidably mounted on said sleeve, a pinion on the housing adapted to mesh with the gear on the fly-wheel, a pair of spirally wound springs in said housing, said housing having recesses therein to receive the inner ends of the spring, said springs being spirally wound to provide track-ways, a plate secured to the outer ends of said springs, and pins rising from said sleeve adapted to extend between the springs and guided thereby, whereby the housing is moved inwardly and outwardly, said plate having lugs thereon, and said housing having recesses therein to receive said lugs, said recesses being larger than the lugs whereby rotary movement of the plate is permitted.

6. In combination with an engine fly-wheel, a gear on the fly-wheel, a starting motor, and an armature shaft on the motor, of a starter drive comprising a sleeve secured to the armature shaft, a housing slidably mounted on said sleeve, a pinion on the housing adapted to mesh with the gear on the fly-wheel, a pair of spirally wound springs in said housing, said housing having recesses therein, to receive the inner ends of the spring, said springs being spirally wound to provide track-ways, a plate secured to the outer ends of said springs, and pins rising from said sleeve adapted to extend between the springs and guided thereby, whereby the housing is moved inwardly and outwardly, said plate having lugs thereon, and said housing having recesses therein to receive said lugs, said recesses being larger than the lugs whereby rotary movement of the plate is permitted, and a cover secured to said housing and extending over the sleeve and against the plate whereby said plate and springs are held in position.

7. In combination with an engine fly-wheel, a gear on the fly-wheel, a starting mo-

tor and an armature shaft on the motor, or a starter drive comprising a housing slidably mounted on the armature shaft, a pinion on the housing, spirally wound springs in the housing, means securing said springs to the housing at one end thereof, pins rising from the armature shaft and extending between the springs, said springs forming a spiral track-way in which said pins move, a plate secured to the other end of said springs, lugs on the plate, said housing having recesses therein to receive said lugs whereby a drive is effected between the armature shaft and the housing.

15 In testimony whereof, I affix my signature.
GEORGE H. HOWARD.
